United States Patent Office

NATHANIEL F. STONE, OF CHICAGO, ILLINOIS.

Letters Patent No. 76,669, dated April 14, 1868; antedated April 1, 1868.

IMPROVEMENT IN CAN-OPENER.

The Schedule referred to in these Letters Patent and making part of the same.

TO ALL WHOM IT MAY CONCERN:

Be it known that I, NATHANIEL F. STONE, of the city of Chicago, in the county of Cook, and State of Illinois, have invented certain new and useful Improvements in Tools for Opening Cans; and I do hereby declare that the following is a full, clear, and exact description thereof, reference being had to the accompanying drawings, making a part of this specification, in which—

Figure 1 represents a side view,

Figure 2 a top view,

Figure 3 a top view of the cutter-plate detached, and

Figure 4 a reverse view.

Like letters refer to the same parts in all of the figures.

The nature of my invention consists in constructing a tool or knife for opening cans such as are used for oysters, sardines, &c., so as to preserve the can for future use, by making the tool so as to cut out a circular piece of a size suited to the size of the can, or to its preservation, which is accomplished by making the bar of a single piece, and slotting it, and providing the slot with an adjustable blade or cutter.

To enable others skilled in the art to make and use my invention, I will describe its construction and operation.

The bar B is made of steel or other suitable metal, and from the handle A to the point D it is from three and one half to four inches in length. The outer end D is made round, and turned down so as to form a shoulder, when it is again bent forward on a line or near a line with the plate, and brought to a sharp point, which, when inserted through the tin, forms a hook, which prevents the implement from lifting or raising out when in operation. It should be so turned at the shoulder that when in operation it will, at the point of intersection, be vertical, or nearly so. The bar B is also provided with a slot, C, for the insertion of a movable knife or cutter, which slot is about two inches in length and one-fourth of one inch in width.

The cutter is usually made entirely of steel, which I make by taking a suitable plate, b, and turning down the point d for the knife, as shown, and at the other end turning up a piece, a, the same in width as the width of the slot C, which projects upwards sufficiently far to prevent the knife from turning when the cutter is attached to the plate B by a single screw, e. It is immaterial whether the heel or piece a projects entirely through the slot or not. The knife d is about one-half of one inch in length at its longest point, and is made with a receding cutting-edge, which form of cutter I have, by experiments, found to be the best in cutting tin or other thin metals in form of cans, or when hollow and cut from the outside. The angle shown, being about forty-five degrees, is the best angle for the cutter-blade or knife. This cutter is attached to the plate by a single screw, e, and fastened by the thumb-nut e on the opposite side.

It will be seen from its construction that it can be adapted to any size of cans readily, and will cut out in a circular form the original cap in oyster-cans, so that they can be refilled or used for other purposes; also, one which will not slip out when in use, and one which is readily adjusted, and not liable to get out of order in use.

Having thus fully described my invention, I am aware that a slotted bar, with bent point and a knife, has been heretofore patented to S. D. LeCompte, and I do not claim them as my invention; but

What I claim as new, and desire to secure by Letters Patent, is—

The plate b, provided at one end with a cutter-blade, d, and at the opposite end with a projection or heel, a, in combination with the screw e and the plate or slotted bar B, substantially as specified.

N. F. STONE.
